Attorney

UNITED STATES PATENT OFFICE.

GEORGE DUMAS, OF WALHALLA, NORTH DAKOTA.

ENVELOP.

No. 906,121.

Specification of Letters Patent.

Patented Dec. 8, 1908.

Application filed May 13, 1908. Serial No. 432,712.

To all whom it may concern:

Be it known that I, GEORGE DUMAS, a citizen of the United States, residing at Walhalla, in the county of Pembina and State of North Dakota, have invented a new and useful Envelop, of which the following is a specification.

This invention relates to an improvement in envelopes and more particularly to that type known as "safety envelopes."

The invention has for one of its objects to provide an envelop having means for immediately detecting surreptitious opening thereof.

15 A further object of the invention is to provide an envelop having means for facilitating the unsealing and opening thereof for the purpose of removing its contents.

In the drawings:—Figure 1 is a perspective view of the invention, showing the envelop sealed. Fig. 2 is a rear elevation thereof. Fig. 3 is a rear elevation, showing the envelop in an open position, and Fig. 4 is a vertical sectional view of the envelop, 25 taken on the line 4—4 of Fig. 2.

Similar reference numerals designate corresponding parts in all the figures of the drawings.

Referring to the drawings, 1 designates the 30 front of the envelop having side flaps 2—2^a, which are adapted to be folded rearwardly and to engage, by mucilage or other adhesive, the back 3 of the envelop. Integral with the front 1 is the top flap 4 adapted to 35 fold rearwardly upon the back 3 and thereby close the opening 5 of the envelop. The top flap 4 is provided with side flaps 6—6 which are integral with the flaps 2—2^a of the front 1, and are adapted to fold rearwardly and to 40 engage by an adhesive, the rear of the flap, and in this manner, form a reinforcing strip. The top flap is further provided with a rearwardly folded horizontal or top strip 7, adapted to be secured to said flap by an adhesive, and also, to form a guideway 8. An 45 opening 9 is provided in the flap 2^a and is located below the opening 5, at a point which substantially registers with the guideway 8 when the top flap 4 is folded. Passing 50 through this opening 9, and preferably extending to the bottom of the envelop is a tape, cord or any other suitable means 10, which is arranged under the side flap 2^a, and is retained therein by glue or any suitable 55 adhesive. This tape or cord 10 extends from the opening 9 to the opening 8^a of the

guideway 8 of the top flap 4, and thence through said guideway and out through the opening 8^a. A sealing device 11, preferably made of paper and covered by an adhesive on 60 one side, is provided with an opening 11^a by means of which the free end of the cord or tape is secured. To further seal the envelop, a second seal is employed having one end 12 thereof secured to the back 3 of the envelop 65 and the other end 12^a free so as to permit of sealing the top flap 4.

From the foregoing, it will be readily apparent that to close and seal the envelop, the operator first folds the top flap rearwardly, and then, by using the seal 11 as a finger-piece, draws the tape or cord 10 until tight, as clearly shown in Fig. 2 of the drawings. Then, the operator still keeping the tape or cord taut, secures the seal 11 to the front 1 75 of the envelop, as shown by reference to Fig. 1 of the drawings. A stamp 14 is then secured to the envelop over the tape or cord 10, thereby sealing the cord or tape. The free end 12^a of the rear seal is then secured to the 80 top flap 4 of the envelop, thereby sealing the said flap to the envelop. Thus, it will be readily seen, that the stamp acts as a check against fraudulent opening of the envelop, because to open the same, the seal 11 has to 85 be detached and the stamp broken by movement of the cord or tape 10. The operator then inserts his (or her) thumb under the top flap 4 at the left hand corner of the envelop. The thumb is then passed along under said flap, breaking the seal 12 and then continued until the right hand corner of the envelop is reached. By grasping the flap 4 between the thumb and forefinger, it can quickly be 90 raised to an upright position, thereby leaving the envelop open to extract the contents. 95

Changes in the form, size, proportion and the minor details of construction, within the scope of the appended claims, may be made without departing from the spirit or sacrificing the advantages of the invention.

Having thus fully described my invention, what I claim as new, and desire to secure by Letters Patent, is:—

1. An envelop comprising a body portion, 105 a flap secured thereto and provided with a guideway longitudinally thereof, and fastening means having one end secured to the body portion at one end thereof, then passing through the guideway of the flap to the other 110 end of the envelop, and then over the face of the envelop where it is sealed.

2. An envelop comprising a body portion, a flap secured thereto and provided with a longitudinal guideway, a fastening cord or tape having one end secured to one end of the body portion, and then passed through the guideway of the flap to the other end of the envelop, and then over the face of the envelop where it is sealed.
3. An envelop comprising a body portion, 10 a top flap secured thereto and provided with a guideway, a fastening means having one end secured to the body portion and the free end passing through said guideway, and a seal mounted on the free end of the fastening means and adapted to engage the envelop and thereby secure the top flap in its closed position.
4. An envelop comprising front and back portions, side flaps integral with one of the 20 portions and adapted to secure the portions together, a top flap integral with the front portion and provided with a guideway, a fastening device having one end secured in one of the side flaps, and arranged to pass through and beyond the guideway, and a seal secured to the free end of the fastening member and adapted to engage the envelop
- and thereby retain the top flap in a closed position.
5. In an envelop, front and back portions, 30 side flaps integral with one of the portions and adapted to secure said portions together, a top flap integral with the front portion and provided with a longitudinal guideway, an opening arranged in one of the side flaps, a 35 fastening device having one end thereof passing through said opening and secured under said flap and the other end arranged to pass through and beyond the guideway of the top flap, a seal secured to the free end of the fastening device and adapted to engage the front portion of the envelop and thereby retain the top flap in a closed position, and a second seal secured to the back portion of the envelop and adapted to seal the top flap 40 against opening.
- In testimony, that I claim the foregoing as my own, I have hereto affixed my signature in the presence of two witnesses.

GEORGE DUMAS.
